UNITED STATES PATENT OFFICE.

HANS SCHLOSSSTEIN, OF CHICAGO, ILLINOIS.

APPARATUS FOR TREATING OILS.

1,296,013.

Specification of Letters Patent.

Patented Mar. 4, 1919.

Application filed January 21, 1918. Serial No. 212,902.

To all whom it may concern:

Be it known that I, HANS SCHLOSSSTEIN, a subject of the Emperor of Germany, and a resident of Chicago, in the county of Cook and State of Illinois, have invented certain new and useful Improvements in Apparatus for Treating Oils; and I do hereby declare that the following is a full, clear, and exact description thereof, reference being had to the accompanying drawings, and to the characters of reference marked thereon, which form a part of this specification.

This invention relates to a novel apparatus for deodorizing or for hardening oils, or both, and refers more particularly to improvements in such apparatus designed to promote the intermingling of oil being treated with the gas, steam or other agent by which it is treated. The invention also relates to a combined oil deodorizing and oil hardening apparatus so arranged that oil may be first treated therein to deodorize it and subsequently, without removing it from the kettle, be treated for hardening the deodorized oil, thereby conserving heat, avoiding waste of oil, and effecting a saving of time in handling the oil.

The invention consists in the combination and arrangement of the parts shown in the drawing and described in the specification and is pointed out in the appended claims.

The figure of the drawing is an axial vertical section of an apparatus embodying my invention.

The apparatus embraces a reservoir or kettle 10, having an intake pipe 11 and a normally closed outlet or draw-off branch 12. The reservoir is jacketed and steam and water may be admitted to the jacket through the respective pipes 14 and 15, and may be drawn off therefrom through the respective pipes 16 and 17. The bottom of the reservoir is tapered toward the outlet 12 and the top of the reservoir is likewise tapered toward a restricted central top opening that is surrounded by a neck 10^a.

Rising from said reservoir is a jacketed shell 18, the jacket of which is equipped with suitable steam and water supply pipe 19—20, respectively, and steam and water draw-off pipes 21, 22, respectively. Said shell is shown as flanged at its base and is bolted to an external flange 24 at the upper end of the neck 10^a.

Within the jacketed shell 10 is a shorter

shell 25. It is arranged centrally within the shell 18 and is fixed at its lower end to an internal flange 26 within the neck 10^a. The annular space 27 between the inner and outer shells is interrupted by baffle flanges 60 28, some springing from one shell and the others from the other shell. The upper end of the inner shell is open and its inner end edge is shaped to produce an annular turned lip 30. 65

The upper end of the outer shell is closed by an end wall or head 31. Opening into the outer shell, through said head 31 is an eduction pipe 32 which is shown as provided with two valved branches 33 and 34. 70

A gaseous or vapor treating agent is introduced into the oil through a perforated ring 35 within the lower portion of the reservoir, and the treating agent is directed to said ring through a supply pipe which is 75 equipped with two valved branches, 36 and 37. A second spray ring 38 is arranged within the lower part of the space 27 between said shells and is equipped with a pipe having two branches 39 and 40. 80

Within the reservoir, and near its bottom, is a suitable pump 41. As shown, it is a centrifugal pump and is adapted to be submerged in the oil in said reservoir. The pump is supported on a frame or bracket 42, 85 shown as made integral with the fitting in which is formed the outlet 12. The eduction pipe 43 of said pump leads to the lower end of the space 27 between the shells 18 and 25, said eduction pipe opening through the internal flange 26.

Arranged centrally, within the inner shell 25, is an operating or power shaft 45 for the pump 41. Said shaft is supported on a bearing 46 at the base of the inner shell and extends through a bearing 47 formed in the head 31 of the outer shell; said bearing being equipped with a suitable stuffing box. The shaft 45 is shown as connected to the rotor shaft of the pump by a link 48. 100

Said shaft is provided within the inner shell 25 with a series of vertically spaced oil diffusing and spraying disks 50. They are made of slightly less diameter than that of the bore of the shell so as to leave passages between them and the inner shell for the flow of oil and the treating agent. The disks are also perforated to permit the oil to pass therethrough in the form of small drops. The shaft is further provided 110

within the reservoir above the oil level with a diffusing disk 52, the upper face of which is preferably tapered downwardly and outwardly.

5   Mounted in said shaft 45 near the top of the outer shell is a conical deflector 55 which cooperates with a fixed, centrally apertured conical partition 56 that is supported in any suitable manner above and spaced from the said deflector 55.

10   The operation of the apparatus for deodorizing oil is as follows:

15   The kettle or reservoir 10 is charged through the inlet opening 11 to about the depth indicated in broken lines in the drawing. The valved eduction pipe 33 is opened and the valve of the branch 34 is closed. Said pipe 33 is connected to a condenser which operates under a suitable negative 20 pressure to produce a negative pressure condition within the apparatus. Pipe 36 is connected with a deodorizing agent, such, for instance, as superheated steam. The valve of said pipe 36 is opened while the 25 valve of the pipe 37 is closed. The steam entering through the pipe 36 is discharged from the perforated ring 35 upwardly through the body of the oil in the reservoir and through the inner shell 25, and is drawn 30 off from the upper end of the shell through the pipe 33. The pump 41 is rotated at a suitably high speed by power connected thereto through the shaft 45, and the oil within which the pump is submerged is conducted 35 through the pipe 43 to the space 27 between the inner and outer shells. At the same time, a deodorizing agent, as superheated steam, is admitted through the pipe 39 to the perforated ring 38 and to said 40 space 27, the valve of the branch pipe 40 being closed. The pressure exerted by the pump is such as to lift the oil to the top of the inner shell 25, and during the passage of the oil from the lower end to the upper 45 end of the space 27, the rising body of oil is broken up by the baffle flanges 28 so as to effect an intermixture of the steam with the oil. The oil charged with a portion of the steam, flows over the inwardly turned lip 30 at the top of the inner shell 25 into said shell and upon the disks 50, which are rapidly rotating. The centrifugal action of said disks causes a portion of the oil to be thrown outwardly against the inner wall of 50 said shell 25 and to flow down therealong. Other portions of the oil pass through the perforations of the disks in small drops. The descending films and drops of oil are met by the ascending stream of the deodorizing 55 agent, as the superheated steam, which is forced upwardly through the body of the oil by reason of its pressure, and also by reason of the negative pressure induced through the pipe 33. The counter currents or streams 60 of descending oil and ascending steam has

the effect to bring the steam and oil into intimate contact with each other; and this intimate contact is promoted or increased by reason of the breaking up or division of the oil into drops, due to the passage thereof 70 through the perforations of the disks 50. The superheated steam and a portion of the oil are carried upwardly to the top of the outer jacketed shell 18. The conical deflector plate 55 prevents the direct passage 75 of the steam and oil from the shell into the eduction pipe 33. The lighter portions of the oil, to be removed in the deodorizing process, are, however, gradually carried through the space between the depending 80 annular portion of the reflector 55 and the wall of the outer shell and through the space between said deflector and the apertured partition 56; and thence outwardly through the eduction pipe 33. The pump 85 41 maintains a continuous circulation of the oil upwardly through the space 27 and downwardly through the inner shell 25, in falling through which the oil meets the counter current of the deodorizing agent. 90

During the time that the deodorizing agent, as superheated steam, is being forced upwardly through the oil, and while the circulation of the oil is being maintained through the apparatus, a heating agent, as 95 steam, is passed through the reservoir jacket by way of the pipes 14 and 16 and through the jacket of the shell 18 by way of the pipes 19 and 20, so as to maintain the walls of said reservoir and shell heated and thereby maintain the proper temperature of the oil while being treated. This process is continued until the oil is properly deodorized, whereupon the valve of the pipe 36 is closed to shut off the supply of the deodorizing 105 agent. Thereafter, cooling fluid is circulated through the reservoir jacket by way of the pipes 15 and 17 and through the jacket of the shell 18 by way of the pipes 24 and 21 until the oil is reduced to a proper 110 temperature, either for removing it from the apparatus or for further treating the oil for other purposes.

The apparatus is so designed that the oil may be treated to harden the same without 115 removing it from the reservoir and by employing similar cycles of circulation of the oil and a proper hardening agent such as hydrogen. When the oil is to be so hardened in the same apparatus, the valves of 120 the pipes 36 and 39 for the deodorizing agent are closed and the valves of the pipes 37 and 40 are opened. The said pipes 37 and 40 are adapted to be connected to a suitable supply of a gaseous-hardening agent, as hydrogen under pressure, said gas to be forced upwardly through the body of oil in the reservoir from the perforated ring 35 and through the annular space 47 from the perforated ring 38. The valve of the eduction 125 130

pipe 33 is also closed and the valve of the branch 34 is opened. Said latter branch is adapted to be connected to a suitable receptacle through which the hardening agent is 5 passed for the recovery of said agent. In practice, a small quantity of a suitable catalytic agent is mixed with the oil which acts in conjunction with the gas discharged from the perforated rings 35 and 38 to harden 10 the oil. In practice, I may employ as the catalytic agent a small quantity of nickel and may employ hydrogen as the gaseous agent for effecting the hardening of the oil. The catalytic agent may be introduced into 15 the system through the pipe 11. During the hardening process, the apparatus may be maintained at the proper temperature by the circulation of a heating fluid through the jackets of the reservoir and outer shell, 20 and after the hardening process has been completed the apparatus is cooled by the circulation of a cooling fluid through said jackets.

After the process of either deodorizing or 25 hardening the oil is completed, the charge of oil is drawn off through outlet 12, it being understood that the said outlet is connected with a suitable valved pipe which is normally closed.

30 An important advantage of the construction described is the large area of contact of the oil with the treating agent, this contact being effected both by reason of bringing the treating agent against the films of streams 35 of oil which flows up along the outer wall of the inner shell, and broken up by the baffle elements 28, and flows in the form of a thin film down the wall of the inner shell, and the contact is promoted by reason of 40 the subdivision of the oil due to the passage thereof through the perforations of the disks 50. By thus treating the oil in both upward and downward flow of the circuit of its travel and breaking up streams of flow in 45 both parts of the circuit, the treating of the oil may be hastened, and the capacity of a given plant equipped with my improvements increased. Furthermore, this construction decreases the overall length of the 50 apparatus, the oil being under treatment in all parts of its circuit. Further, the quality of the product is improved, as it is possible to apply a special range of temperatures and pressures especially favorable to 55 the treatment of the oil.

Another advantage of the construction described lies in the dual capacity of the apparatus to deodorize and harden a batch of oil without removing it from the apparatus, 60 thus resulting in the saving of heat and also of time in handling the oil and the consequent waste. A further advantage lies in the fact that the oil cannot be transferred from one apparatus to another without appreciable deterioration of the oil with re-

spect to its deodorization. Another general advantage of the duplex construction is that the plant equipment is thereby simplified and reduced in cost.

I claim as my invention:

1. Apparatus for treating oil comprising means for circulating oil in a defined circuit, with means to force streams of a treating agent through the oil in both the rising and descending parts of said circuit, and means to spray the oil through a part of the circuit in which it is subjected to a counter directed stream of treating agent. 70

2. Apparatus for treating oil comprising means for circulating oil in a defined closed circuit, with means to force streams of a treating agent through the oil in both parts of said circuit, and means to spray the oil through a part of the circuit in which it is subjected to a counter directed stream of treating agent, combined with means to present a film contact of the oil to said treating agent. 80

3. Apparatus for treating oil comprising means for circulating oil in a closed circuit, with means to force a counter directed stream of treating agent through the oil in one part of said circuit, means to spray the oil through that part of the circuit in which it is subjected to the counter directed stream of treating agent, and means to force a stream of treating agent through said circuit in the part of said circuit which travels in the same direction as said stream of treating agent. 90

4. Apparatus for treating oil comprising a reservoir, inner and outer shells rising therefrom and spaced to produce between them an annular passage, with the inner shell in communication with said reservoir, means to effect a circulation of oil upwardly through said annular passage and downwardly through the inner shell, means to force a treating agent upwardly through said inner shell counterwise to the downflow of oil therethrough, and means to effect a spraying subdivision of the oil in drops in said inner shell. 105

5. Apparatus for treating oil comprising a reservoir, inner and outer shells rising therefrom and spaced to produce between them an annular passage, with the inner shell in communication with said reservoir, means to effect a circulation of oil upwardly through said annular passage and downwardly through the inner shell, means to force a treating agent upwardly through said inner shell counterwise to the downflow of oil therethrough, and means to effect a spraying subdivision of the oil in drops in said inner shell, with means to spread a downwardly flowing film of oil on the wall of said inner shell in contact with which the treating agent rises. 120

6. Apparatus for treating oil, comprising 130

4
 a reservoir, inner and outer shells rising therefrom and spaced to produce between them an annular passage, with the inner shell in communication with said reservoir,
 5 a pump for forcing the oil upwardly through said annular passage and downwardly through said inner shell, a rotative operating shaft for said pump extending through said inner shell, perforated disks
 10 on said shaft and turning therewith, and means to force a treating agent upward through said inner shell.

7. Apparatus for treating oil, comprising a reservoir, inner and outer shells rising therefrom and spaced to produce between them an annular passage, with the inner shell in communication with said reservoir, a pump for forcing the oil upwardly through said annular passage and downwardly.
 15 20 through said inner shell, a rotative operating shaft for said pump extending through said inner shell, perforated disks on said shaft and turning therewith, and means to force a treating agent upward through said inner shell, together with means to force a treating agent upwardly through said annular passage.

8. Apparatus for treating oil, comprising a reservoir, inner and outer shells rising therefrom and spaced to produce between them an annular passage, with the inner shell in communication with said reservoir, means to effect a circulation of oil upwardly through said annular passage and downwardly through the inner shell, an operating shaft for said circulating means extending
 30 35

through said inner shell, perforated disks on said shafts and turning therewith, and a diffusing disk on said shaft within said reservoir and above the oil level therein.

40

9. Apparatus for deodorizing and hardening oils, comprising a receptacle with means to effect the circulation of oil in a closed circuit through the apparatus, and separate means to force a deodorizing agent or a 45 hardening agent through the oil in both sides of the circuit to separately deodorize and harden the oil.

45

10. Apparatus for treating oil to deodorize and harden the same, comprising a reservoir, inner and outer shells rising therefrom and spaced to produce between them an annular passage, with the inner shell in communication with said reservoir, means for effecting a circulation of oil upwardly 50 through the annular passage and downwardly through the shell, a perforated pipe within the reservoir adapted to be submerged by the oil, and a perforated pipe at the bottom of said annular space, each of 55 said perforated pipes being connected to branched valve pipes whereby treating agents of different characters may be separately delivered to said perforated rings.

50

In testimony whereof I claim the foregoing as my invention, I hereunto append my signature at Chicago, Illinois, this 14th day of January, 1918.

HANS SCHLOSSSTEIN.
